UNITED STATES PATENT OFFICE.

GEORGE A. JOHNSON, OF CHICAGO, ILLINOIS, ASSIGNEE TO WILLIAM H. MINER, OF CHICAGO, ILLINOIS.

DRAFT-RIGGING FOR RAILWAY-CARS.

1,073,241.

Specification of Letters Patent. Patented Sept. 16, 1913.

Application filed December 26, 1912. Serial No. 738,536.

To all whom it may concern:

Be it known that I, GEORGE A. JOHNSON, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

My invention relates to improvements in draft rigging for railway cars.

One object of my invention is to provide 15 a draft rigging of comparatively low capacity under pulling strains, and of relatively high capacity under buffing movement.

A further object is to have both the 20 spring and friction compression resisting parts in which the springs only are employed to resist pulling strains, and both the springs and friction members are employed in resisting buffing shocks.

25 This application discloses an improvement upon the invention shown by my pending application, Serial No. 725,603, filed October 14, 1912.

In the drawings Figure 1 is a side elevation partly in central longitudinal section on line 1—1 of Fig. 2 of a draft rigging embodying my invention. Fig. 2 is a plan view partly in horizontal section on line 2—2 of Fig. 1. Fig. 3 is an elevation 30 partly in central longitudinal section showing the position of the parts of the draft rigging in full compression under pulling strain. Fig. 4 is an elevation partly in central longitudinal section showing the position 35 of the parts in draft rigging in full compression in buff.

Referring to the drawings 5, 5 represent center sills or parts of the car frame to which the draft rigging is attached, 6 the 45 end sill, 7 the buffer block, 8 the draw-bar carry iron—all of usual construction. Secured between the center sills is the bolster filler block 10, centrally provided at its forward end with the vertical groove or recess 50 11. The draw-bar 12 is provided with a transverse slot 13. The compression resisting member 14 is mounted between the center sills. The front faces 15, 15 of the bolster filler block 10 and on either side of the 55 recess 11 serve as rear stop members. The

front stop members 16, 16 are suitably secured to the center sills, and are with the adjacent portions of the center sills provided with the transverse slots 17, 17 for the passage of the coupler key 18.

The draft yoke 19 consists of a U-shaped member 20 having the upper and lower limbs 21 and 22 respectively riveted to the hollow box like head 23, which receives the rear end of the draw bar, and which head 65 is provided with the transverse slots 24 registering with the slots 17 in the center sills and front stop members, permitting the passage of the coupler key 18. All of the aforesaid slots are suitably longitudinally extended to permit the rearward movement therein of the coupler key on buffing action of the draft rigging, and slots 17 are elongated to permit forward movement therein of the coupler key in draft action of the 75 draft rigging.

The front follower 25 is of usual construction, and passes between the upper and lower limbs 21 and 22 of the draft yoke. The lower limb of the draft yoke rests upon the tie-plate 26, which is secured at either end to the lower surfaces of the center sills, and serves to support the draft yoke and the compression resisting member 14 which rests between the two limbs of the said yoke. 80 The compression resisting member 14 embraces a shell 27, friction elements 28, and spring elements 29 therein, the connecting rod 30 and the rear follower 31, and thrust member 35. The shell 27 is hollow, and preferably cylindrical in form or circular in cross section, open at its forward end 32, which forward end is preferably provided with an external annular flange 33. The rear follower 31 is preferably a rectangular plate, which in preferable construction is integral with the shell 27. The rear end of the shell is provided with the opening 34, preferably circular in form. A thrust member 35 adapted to pass through the said opening engages the rear portion of the draft yoke at its rear end 36, and the spring elements 29 at its forward end 37. In preferable construction the said thrust member is cylindrical in form, having at its forward end an annular shoulder 38 which engages the shoulder 39 formed by the rear portion of the shell.

The spring elements 29 comprise preferably an outer spring 40 and an inner 110

spring 41 nested therein, both being seated at their rear ends against the front face 42 of the thrust member 35, and at their forward ends against the friction elements 28.

5 The friction elements 28 comprise a set of annularly arranged segmental friction shoes 43, preferably three in number and of well known construction, adapted to engage the internal friction face 44 of the shell. A wedge 45, preferably of pyramidal shape and adapted to spread the friction shoes, and having wedging faces 46 between each of which and the wedging face 47 with which the internal portion of each friction shoe is provided is seated an anti-friction roller 48.

In preferable arrangement the friction shoes 43 are provided with internal shoulders 49 against which the forward end of 20 the inner spring 41 is seated, the outer spring 40 being forwardly seated against the rear ends 50 of the friction shoes. The wedge 45 is provided with a recess 51 to receive the head 52 of the connecting rod 25 30, which passes rearwardly through the wedge and a perforation 53 in the thrust member 35, and is provided at its rear end with the nut 54.

On rearward movement of the draw bar 30 the coupler key 18 slides within the rearwardly extended slots 17 in the center sills 5 and front stop members 16, the shell is held against rearward movement by the rear stops 15, and through the front follower 25 35 both the friction and spring elements of combined relatively high shock absorbing capacity are compressed within the shell. On full compression the parts are in the relative positions illustrated by Fig. 4 of the drawings. On forward movement of the draw bar the coupler key is in tractive engagement with said draw bar in slot 13 thereof, and with the draft yoke in the slot 24 thereof. The front follower 25 engages the front stop 40 member 16, and by means of the draft yoke 19 the thrust member 35 is drawn forwardly, and without movement of the shell the springs are compressed between said thrust member 35 and the front follower in combination with the friction elements. In forward movement of the draw bar the friction elements are stationary, and substantially the entire work of compression resistance is done by the spring. Upon full compression 45 50 of the springs on pulling movement of the gear the parts assume the position illustrated in Fig. 3 of the drawings.

I claim:—

1. In a railway draft rigging, in combination, a draw bar, a front follower, a shell,

65 springs and friction elements within the shell, a rear follower rigidly secured to the shell, a draft yoke, a draw bar and a thrust member, front and rear stop members, the rear follower being in engagement with the rear stop member, the shell having an opening for the passage of the thrust member, the said thrust member engaging the draft yoke at its one end and the springs at its other end.

70 2. In a draft rigging for railway cars, the combination of a draw bar, stop members, draft yoke and followers, with a shell, friction elements and springs within the shell, with a thrust member, the shell being 75 provided with an opening to receive said thrust member, the said thrust member engaging the yoke at its one end and the springs within the shell at its other end, the rear follower being rigidly secured to the shell, and engaging the rear stop members on both forward and rearward movement of the draw bar, the springs being compressed between the thrust member and friction elements on forward movement of 85 the draw bar without bringing the friction elements into frictional action.

90 3. In a draft rigging for railway cars, in combination, a draw bar, front and rear stop members, a front follower, a shell, a rear follower rigidly secured to said shell, friction elements and springs within the shell, a thrust member and a draft yoke, the shell having an opening at either end, the thrust member passing through the rear 95 opening in the shell and engaging the draft yoke back of the rear stop members, the friction members engaging the front follower, the said spring being seated between the friction members and the thrust member. 100

105 4. In a draft rigging for railway cars, in combination, a draft yoke, a draw bar connected to said yoke, a front follower, front and rear stop members, a friction shell within the yoke, a rear follower rigidly secured to said shell, friction elements and spring elements within the shell, and a thrust member, the shell being stationary and the rear follower in engagement with the rear stop members, the thrust member extending rearwardly of the rear follower and engaging the yoke at its rear end, and the springs within the shell at its forward end, the friction elements being disposed between the front follower and the said spring. 110
